UNITED STATES PATENT OFFICE.

CHARLES P. SEARLES, OF COLUMBUS, OHIO.

WRINGER.

SPECIFICATION forming part of Letters Patent No. 547,402, dated October 1, 1895.

Application filed December 17, 1894. Serial No. 532,112. (No model.)

To all whom it may concern:

Be it known that I, CHARLES P. SEARLES, a citizen of the United States, residing at Columbus, in the county of Franklin and State 5 of Ohio, have invented certain new and useful Improvements in Wringers; and I do hereby declare the following to be a full, clear, and exact description of the invention, such as will enable others skilled in the art to 10 to which it appertains to make and use the same.

My invention belongs to that class of wringers in which the device for giving pressure to the rollers serve to clamp the wringer to the side of a tub.

15 The object of my invention is to make certain improvements in the construction of such wringers.

In the accompany drawings, Figure 1 illustrates a side elevation; Fig. 2, an end elevation. Fig. 3 is a vertical sectional view taken on a plane indicated by the line $\alpha\alpha$ of Fig. 1.

Like characters of reference in the drawings designate corresponding parts.

1 designates the side parts of the frame, 2 25 a cross-piece extending between the upper ends of the sides. The lower parts of the side pieces are held together by a board 3. The side pieces 1 are made with vertical slots 4, which receive the journal-boxes 5 and 6 of 30 the upper and lower rollers 7 and 8, respectively. The journal-boxes of the lower roller have arms 9 and 10, extending in nearly opposite directions therefrom. Extending between the outer ends of the projections 9 is a 35 roller 11, which, also, as will be seen herein-after, serves as a handle for releasing the clamping device. This clamping device, which is designated 12, comprises two side pieces having a bar extending between their 40 lower ends. The side pieces of the clamp 12 are pivoted upon projections 13, and their upper ends are pivoted to the arms 10, extending from the journal of the lower roll. When the lower roller is elevated the inner ends of 45 the arms 10 are drawn upward, thereby loosening the clamp, and when the lower roller is forced downward the arms force the upper ends of the clamp outward, bringing the lower end thereof into engagement with the tub. 50 Extending between the sides 1 of the wringer-

frame and above the upper roller is a bar 14, the ends of which rest upon the journal-boxes of the upper roller or upon small elastic springs 15, of rubber or other substance, upon the journal-boxes. The bar 14 is provided at 55 the upper side of its middle with a fixed screw 15', having on its upper end a threaded nut 16 with a cylindrical cap 17. This cap fits and is rotatable by turning the nut in a cylindrical socket 18 in the cross-piece 2. Piv- 60 oted to ears 19 above the cap 17 is a hand-lever 20, having an eccentric 21', which acts against the upper end of the cap. By depressing this lever the bar 14 is depressed, and consequently the upper roller against the 65 lower.

To put the wringer in position for use the hand-lever 20 is raised and the lower part of the clamping-frame sufficiently separated from the main frame to permit it to be placed 70 on the edge of the tub. The nut is then adjusted to such a position that the desired pressure between the rollers will be attained when the hand-lever is depressed. The pressure on the rollers, also, through the arms 10, 75 throws the upper end of the clamping-frame outward and the lower end inward sufficiently to secure the wringer to the tub.

To remove the wringer the hand-lever 20 is elevated, when the device may be lifted off 80 the tub. If the clamp sticks upon the attempt to remove the wringer, it may be detached by lifting the roller 11. The slots in the side pieces of the wringer-frame are made with stops or shoulders 21 to prevent the upper 85 roller from falling into contact with the lower roller when the wringer is not in use, because when the rollers are left in contact with each other water is retained between them, which causes the rubber to rot. A drip-board 22 90 conducts the water wrung from the clothes into the tub.

What I claim, and desire to secure by Letters Patent, is—

1. In a wringer, the frame the side pieces of 95 which have slots, two wringer rollers having journal boxes movable in said slots, a clamp pivoted to the wringer frame, arms pivoted to the clamp and connected with the journal boxes of the lower roller whereby depressing 100

the lower roller will close the clamp, and means for depressing said lower roller, substantially as described.

2. In a wringer, the frame the side pieces of which have slots, two wringer rollers having journal boxes movable in said slots, the lower journal boxes having arms projecting in substantially opposite directions therefrom, a bar connecting one pair of said arms, the other

being hinged to a clamp pivoted on the wringer frame, and means for depressing said rollers, substantially as described.

In testimony whereof I affix my signature in presence of two witnesses.

CHARLES P. SEARLES.
